(57) **CLAIM**

The ornamental design for a garden planter with light, as shown and described.

DESCRIPTION

FIG. 1 is a rear elevation view of a garden planter with light showing our new design;

FIG. 2 is a front elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a top, left, rear perspective view thereof;

FIG. 8 is a top, right, rear perspective view thereof;

FIG. 9 is a top, right, front perspective view thereof;

FIG. 10 is a top, left, front perspective view thereof;

FIG. 11 is a bottom, left, rear perspective view thereof;

FIG. 12 is a bottom, right, rear perspective view thereof;

FIG. 13 is a bottom, right, front perspective view thereof;

FIG. 14 is a bottom, left, front perspective view thereof; and, FIG. 15 is an enlarged view of portion 15 shown in FIG. 14. The broken line shown is for the purpose of illustrating portions of the garden planter with light and forms no part of the claimed design.

The dot-dash broken lines represent boundaries of the enlarged portion and form no part of the claimed design.

1 Claim, 15 Drawing Sheets
